UNITED STATES PATENT OFFICE

ELIJAH E. DEPUTY, OF MILLVILLE, NEW JERSEY.

RAZOR-SHARPENER.

SPECIFICATION forming part of Letters Patent No. 668,503, dated February 19, 1901.

Application filed June 19, 1900. Serial No. 20,872. (No model.)

To all whom it may concern:

Be it known that I, ELIJAH E. DEPUTY, a citizen of the United States, residing at Millville, in the county of Cumberland and State of New Jersey, have invented a new and useful Razor-Sharpener, of which the following is a specification.

The invention relates to improvements in razor-sharpener.

10 The object of the present invention is to improve the construction of razor-sharpener and to provide a simple, inexpensive, and efficient device adapted to enable an inexperienced person to accurately sharpen a razor and capable when a razor is drawn back and forth across it of operating on the same in a manner similar to that which takes place when a razor is honed by hand or on a stationary stone.

20 The invention consists in the construction and novel combination and arrangement of parts hereinafter fully described, illustrated in the accompanying drawings, and pointed out in the claims hereto appended.

25 In the drawings, Figure 1 is a perspective view of a razor-sharpener constructed in accordance with this invention. Fig. 2 is a longitudinal sectional view of the same. Fig. 3 is a detail perspective view of the rotary razor-support. Fig. 4 is a detail view of one of the dished gears.

Like numerals of reference designate corresponding parts in all the figures of the drawings.

35 1 designates a plate or bar provided with a shank 2, which is secured within a handle 3, and the latter may be of any desired construction. The plate or bar is provided with inner and outer longitudinal slots 4 and 5, receiving inner and outer spindles 6 and 7, upon which are mounted inner and outer gear-wheels 7^a and 8. The inner spindle has its inner end reduced and threaded, the reduction forming a shoulder to engage the adjacent face of the plate or bar and the threaded end 9 receiving a nut 10, which is adapted to engage the plate or bar. The slot permits the spindle to be adjusted inward and outward, and the nut clamps the spindle at the desired adjustment. The spindle is provided at its outer end with a head 11, and it receives a rotary rest 12, which has its inner portion fixed

to the inner gear 7^a, which rotates on the spindle. The inner gear is provided with a dished central portion forming a central concavity 55 or recess 13 to receive the inner end of the rotary rest 12, and the teeth of the gear-wheel mesh with those of the outer gear-wheel, as clearly shown in Fig. 1.

The outer spindle, which is provided with a suitable head 14 for engaging the outer gear-wheel, is reduced and threaded to provide a shoulder and to receive a clamping-nut 15, which engages the back of the plate or bar to secure the outer spindle at the desired adjustment. The outer gear 8 is dished to provide a central annular recess or cavity 16 to receive a rotary hone 17, which may be constructed of any desired material. The hone is fixed to the dished gear, and it is provided with a central recess to enable it to clear the head of the screw.

The rotary rest is provided with a reduced outer portion 18, forming a shoulder 19, and the back of the razor to be sharpened is placed on the rotary rest with the edge adjacent to the face of the hone, as indicated in dotted lines in Fig. 2 of the accompanying drawings. By moving the razor back and forth it rotates the rotary rest, and the gearing communicates motion to the rotary hone, which rotates across the edge of the blade, whereby the movement of the hone and the blade is substantially the same as that which is given to a razor in honing it on a stationary stone, and by this construction an inexperienced person may accurately hone a razor by simply drawing it back and forth across the device. A rubber sleeve 20 is arranged upon the reduced outer portion of the rotary rest to enable the necessary friction to be readily created for positively operating the device, and the elasticity of the sleeve, which may be constructed of other material than rubber, cushions the razor and prevents the same from being subjected to any material jar in placing it on the device. The device is adapted to be held in an upright position in one hand, and it may be readily reversed by partially rotating it to arrange the hone against either face of the razor.

100 Although gearing consisting of spur gear-wheels is employed for transmitting motion from the rotary rest to the rotary hone, yet it will be readily apparent that any suitable

means may be employed for effecting this result.

It will be seen that the razor-sharpener is exceedingly simple and inexpensive in construction, that it is adapted to be readily handled to operate it and to reverse it to bring the rotary hone against either face of the blade of the razor, and that it will enable an inexperienced person to properly sharpen a razor. It will also be apparent that by drawing the blade back and forth across the rotary rest the blade is reciprocated and a rotary motion is simultaneously imparted to the hone.

15 What I claim is—

1. A device of the class described comprising a support, a rotary hone, a rotary rest adapted to receive a razor and capable of being rotated by the same when the razor is reciprocated, and means for communicating motion from the rest to the hone to rotate the latter, substantially as described.

2. A device of the class described comprising a support, a pair of gear-wheels mounted on the support and meshing with each other, a rotary hone carried by one of the gear-wheels and a rotary rest mounted on the other gear-wheel, and arranged to receive a razor and capable of being rotated by the same when the razor is reciprocated, whereby the hone will be rotated, substantially as described.

3. A device of the class described comprising a support, a rotary hone, a rotary rest having a reduced outer portion forming a shoulder and adapted to receive a razor, and means for communicating motion from the rotary rest to the hone, substantially as described.

4. A device of the class described comprising a rotary support adapted to receive a razor and to be actuated by the same when the said razor is reciprocated across it, and a rotary hone connected with and operated by the rotary rest and arranged to revolve at the edge of the razor, substantially as and for the purpose described.

5. A device of the class described comprising a support, a rotary hone, a rotary rest connected with and adapted to operate the rotary hone, said rest being provided with a shoulder, and an elastic sleeve arranged on the rest to provide a cushion and to create friction, substantially as and for the purpose described.

6. A device of the class described comprising a pair of wheels connected together and adapted to rotate, said wheels being provided with depressions or cavities, a hone mounted in one of the depressions or cavities, a rest fitting in the other depression or cavity, and means for supporting the wheels, substantially as described.

7. A device of the class described comprising a support having slots, inner and outer spindles having threaded portions passing through the slots and provided with nuts, wheels mounted on the spindles, a rotary hone carried by one of the wheels, and a rotary rest carried by the other wheel and supported by the adjacent spindle, substantially as described.

In testimony that I claim the foregoing as my own I have hereto affixed my signature in the presence of two witnesses.

ELIJAH E. DEPUTY.
